UNITED STATES PATENT OFFICE.

BENJAMIN F. BAILEY, OF ANN ARBOR, MICHIGAN.

CIRCUIT-BREAKER.

1,141,300.

Specification of Letters Patent.

Patented June 1, 1915.

Application filed August 15, 1912. Serial No. 715,217.

To all whom it may concern:

Be it known that I, BENJAMIN F. BAILEY, a citizen of the United States, residing at Ann Arbor, in the county of Washtenaw and State of Michigan, have invented certain new and useful Improvements in Circuit-Breakers, of which the following is a specification.

This invention relates to circuit breakers, 10 and more especially to that class thereof which are adapted for use in connection with sparking or ignition devices for igniting the gas charges of a hydrocarbon engine, and it has for one of its objects the 15 provision of a device of this character whereby the electric current may be very quickly broken subsequent to a flow of current lasting a comparatively long time.

The invention has, furthermore, for its 20 object the provision of a breaker comprising a rotary member which is operated at a pre-determined ratio relative to the main shaft of the engine, and which in turn operates a rotatable member in such a manner that 25 normally the second member will be moved in unison with the first member while, if for any reason the driving shaft of the device should have an accidental backward rotation, as for instance by what is generally 30 known as the "kick-back" of the engine, the second member will be locked against backward rotation and thus prevent damage or destruction of several of the more delicate parts of the device.

The invention has, furthermore, for its 35 object the provision of a novel organization of the make and break devices which in the present instance comprise a secondary comparatively sensitive and quick acting contact member controlled in its action by another or primary member which is directly operated by a device on the driving shaft.

The invention has also for its object the provision of means whereby the operating 40 member for establishing the make and break of the electric current, may be automatically advanced or retarded proportionately to the speed of the shaft of the device, and consequently of that of the engine. In other 45 words: the present device is adapted to combine, in itself, the usual feature of the manual control generally exercised by the operator of the engine in advancing the spark, as the engine gathers speed so as to bring 50 the point of ignition into the proper period of the stroke of the engine piston.

Further objects of the invention will hereinafter appear and be particularly defined in the claims.

The invention has been clearly illustrated 60 in the accompanying drawings, in which similar characters denote similar parts, and in which—

Figure 1 is a face view of a circuit breaker embodying my invention, the supporting 65 case having been removed. Fig. 2 is a side view thereof.

Referring to the drawings, 10 denotes a shaft which, for the purposes of igniting the charges in internal combustion engines, 70 is driven in a fixed ratio from the main shaft of the engine. This shaft is journaled in a hub 11' of a plate 11 which is held on a stationary casing 12 indicated by dot and dash lines. Secured to, and insulated from, 75 the plate 11, are a pair of terminals 13—14 to which suitable conductors may be attached, as usual, and the connection between which terminals is to be established or broken by the mechanism constituting the 80 feature of my present invention. For this reason the terminal 14 is connected by a conductor 15 with a contact maker 16 which consists of a resilient blade extending toward the other terminal 13 and having its 85 rear end attached indirectly to a block 17 which is pivoted on a post or stud 18 for oscillatory movement. For this purpose the block 17 has attached thereto an actuator member 19' which is comparatively stiff in 90 structure and yet may have some degree of resiliency, if desired. This member may be attached directly to the block and preferably support the rear end of the blade 16 above mentioned.

The forward end of the primary actuator 95 19 is bent into hooked form as shown at 19' to engage the forward or free end of the blade 16 which has a contact point adapted to be thrown into engagement with the end 100 of a contact screw 21 adjustable in a bracket or lug 22 projecting from the plate 11, it being understood that this contact screw is insulated from the plate either directly or indirectly.

In the present instance the primary actuator 19 is formed of sheet metal which is bent at its rear portion so that a spring 23 may be attached thereto for the purpose of throwing the actuator 19 downward into the 105 position shown in Fig. 1, it being thus held or limited by an abutment rod 24 adjustable

in a lug 25 also carried by the plate 11. The other end of the spring is attached to an adjusting screw 26 which may be adjusted in a lug 27 to increase or decrease the tension of the spring 23 to the desired degree.

From the foregoing it will be understood, that the position of the parts as shown in Fig. 1 is normal, and that the connection between the terminals 13 and 14 is interrupted notwithstanding the fact that the tendency of the blade 16 is to bring the contact point 20 into engagement with the screw 21, so that consequently in this position of the parts, the hook 19' serves to hold the break at this point open regardless of what the tension of said blade may be. This means that the spring 23 can be very light because it has nothing to do except to swing the primary actuator 19 around the axis of the block 18 and pull the same in contact with the limiting rod 24.

The contact between the point 20 and the screw 21 is made by an operator mounted on the shaft 10 and controlled by a carrier which is rotated by said shaft, turn for turn, and adapted to carry the operator along with it when the shaft moves in one direction, but it will release or be free from the operator if the shaft travels in a reversed direction. The principal object for this construction is: to avoid any breakage of parts if, for some reason or other the shaft should be run in a backward direction, as for instance through a "kick back" or premature explosion in the engine cylinders. Under normal conditions, and in its most simplified form, the carrier may be directly secured to the shaft, but I have in the present instance provided for an automatic regulation whereby the carrier may be moved angularly to the axis of the shaft in a predetermined ratio to the shaft speed so that consequently the contact-operator will also be advanced or retarded in its operation and in the same proportion, thus doing away with the usual manual operating advancing the spark to produce the ignition of the gas charge at the proper moment. The carrier 30 is in the present instance mounted loosely upon the shaft 10, and its arm 30' is connected by a link 31 with a weight lever 32 pivoted at 33 on a disk 34 which is rigidly secured to the shaft 10. A spring 35 is interposed between a projection of the weight lever and the inner end of the screw 36 (the latter being adjustable in a lug 37 carried by the disk 34) so that in this manner the weight lever will be normally swung inwardly by the spring until it comes into contact with an abutment stud 38 also carried by said disk.

The arm 30 of the carrier carries a blade 39 having a hook shaped end 39' which is adapted to engage any one of a series of lips 40' of the operating member 40 which in the

present instance has a pair of cam faces terminating in the lips 40' above mentioned, it being understood that the shaft 10 of Fig. 1 is rotated clock-wise so that consequently the primary member 19 will be raised twice 70 during each rotation of the shaft. Each raising action of the member 19 will therefore be positive and will result in allowing the contact point 20 to engage the screw 21 regardless of how high the hook end 19' is 75 raised. As soon as the drop-off point or lip 41' has passed the end 19' of the primary operator, the spring 23 will immediately swing the member 19 downward again so that its hook end 19' will already be in rapid 80 motion when it engages the free end of the blade 16 which latter has furthermore a tendency of assisting the spring 23 to return the member 19 to its normal or operative position. Of course after the hook 19' has 85 once caught the end of the blade 16, the spring 23 will be the only efficient part for bringing the arm 19 into the position shown in Fig. 1.

This point is particularly emphasized because by this construction the contact existing between the point 20 and the screw 21 may be of considerable duration, and furthermore the break is established very quickly for the reason that the hook 19' is 95 actually in very rapid motion even before it comes into catching engagement with the end of the blade, so that consequently this releasing action partakes more of the nature of a blow than of a gradual movement 100 which will naturally result in the hook end 19' dropping off from the lip 40'. The particular function of the hook end 39' and the lip 40' is that of preventing any centrifugal force on part of the arm 39 to have any effect in lessening its engagement with the actual operator which is consequently moved thereby in what may be considered a locked manner.

If for some reason, as above stated, a retrograde movement should be imparted to the shaft 10, the disk 34 would naturally be rotated likewise, and with it the carrier 30. If then there should be any excessive friction between the blade 39 and the operator 40, there might be a tendency of operating the operator 40 backward also, and for that reason I deem it expedient to provide a check device whereby said operator 40 will be positively held against backward rotation, this 115 device comprising a lever 41 pivoted at 42 and having an arm 43 adapted to bring up against a stop pin 34 on the base plate 11, the lever being swung inward to hold its hook ends 41 normally in the path of the 120 lips 40' above mentioned, by a spring 45 secured to the arm 43 and resting against a pin or stud 46 secured to the base plate 11.

Many changes may be made in the general organization as well as in the particular con- 130

struction of some of the component parts of my improved mechanism, without departing from the spirit of the invention, particularly in the manner in which the operator is advanced or retarded at a rate proportionate to the speed of the engine shaft, since other means for accomplishing the same desired result may be readily substituted for the mechanism herein shown and described. In a like manner the suspension of the contact maker and its operator may be readily changed to suit various requirements, although the present construction enables me to use a comparatively light spring for returning the breaker arm to normal, regardless of the tension under which the contact blade is working relatively to the primary member 19.

I claim:—

- 20 1. In a circuit breaker, stationary and movable contacts, a rotatable shaft, a cam loosely mounted in relation to the shaft and having a plurality of shouldered portions for engaging said movable contact to move the latter into engagement with the stationary contact, a member fixed to rotate with the shaft, and a yieldable arm connected to said member to rotate therewith, said arm being adapted in one direction of rotation of the shaft to engage one of said shoulders on the cam to couple the latter to said member, and being adapted to disengage said shoulder upon rotation of the shaft in the opposite direction, for the purpose described.
- 25 2. In a circuit breaker, stationary and movable contacts, a rotatable shaft, a cam

loosely sleeved upon the shaft and having a plurality of shouldered portions for actuating said movable contact, a member fixed to rotate with the shaft, and a spring arm 40 connected to said member to rotate therewith and having a hook-shaped portion engaging one of said shoulders on the cam in one direction of rotation of said member to couple the cam to said member, said hook-shaped portion being adapted to disengage said shoulder upon rotation of the shaft in the opposite direction.

3. In a circuit breaker, stationary and movable contacts, a rotatable shaft, a cam loosely 50 sleeved upon the shaft having a plurality of shouldered portions for actuating said movable contact, a carrier loosely sleeved upon said shaft having a laterally-extending arm, a member fixed to rotate with said shaft, a connection between said arm and said member, and a spring arm carried by the first-mentioned arm, provided with a hook-shaped portion engageable with one of said shouldered portions upon rotation of the shaft in one direction to couple the cam to said member, said hook-shaped portion being disengagable from the shouldered portions of the cam when the shaft is rotated in the opposite direction. 55

In testimony whereof I affix my signature in presence of two witnesses.

BENJAMIN F. BAILEY.
